UNITED STATES PATENT OFFICE.

NORMAN ELIGAH OTTO, OF SMITH FALLS, AND ALBERT WILSON OTTO, OF OSGOODE STATION, ONTARIO, CANADA, ASSIGNORS OF ONE-THIRD TO WILLIAM R. BOON, OF MONTREAL, CANADA.

WATER-CRANE.

No. 903,105.

Specification of Letters Patent.

Patented Nov. 3, 1908.

Application filed March 9, 1908. Serial No. 420,087.

To all whom it may concern:

Be it known that we, NORMAN ELIGAH OTTO, of Smith Falls, county of Lanark, in the Province of Ontario, Canada, and ALBERT WILSON OTTO, of Osgoode Station, county of Russell, in the Province of Ontario, Canada, both subjects of the King of Great Britain, have invented certain new and useful Improvements in Water-Cranes; and we do hereby declare that the following is a full, clear, and exact description of the invention, such as will enable others skilled in the art to which it appertains to make and use the same.

The invention to be hereinafter described relates to water cranes for supplying the boilers of locomotives, and more particularly to that class of such cranes as are adapted to swing bodily about a pivotal support in order to allow the outer arm to be placed over the manhole of the tender to allow delivery of the water.

Broadly speaking, it comprises a suitable support, a crane pivotally mounted on the support, a sleeve or collar carried by the crane, a locking device carried by the crane and adapted to engage the crane support to lock the crane thereto; means carried by the crane for unlocking it, separate means carried by the sleeve or collar for unlocking the crane, valve actuating means carried by the crane for controlling the flow of water to and from the crane, and means for limiting the movement of the valve.

In order to more clearly disclose the construction, operation and use of the invention, reference should be had to the accompanying drawings, forming part of the present application.

Throughout the several views of the drawings, like reference characters designate similar parts.

In the drawings: Figure 1 is a rear view of the crane; Fig. 2 is a view, showing in detail the relative positions of the crane and water main in full lines; the valve operating mechanism being shown in inoperative position in dotted lines; Fig. 3 is a vertical section through the crane, showing the locking device in section, and one of the means for unlocking the same; Fig. 4 is a front elevation of the locking bolt, the collar and crane support being shown in section; Fig. 5 is a section on line 9—9 of Fig. 2, looking in the direction of the arrow; Fig. 6 is a

section on line 10—10 of Fig. 2, looking in the direction of the arrow; and, Fig. 7 is a section on line 11—11 of Fig. 2, looking in the direction of the arrow.

A shell 1 of tubular form is made fast to a box or casing, in which are placed the valve mechanisms for controlling the flow of water from the main to the crane. Through the shell is passed the upright branch 2 of the crane the lower end of the branch being removably and revolvably seated in a collar 3, which is detachably secured to a valve chamber 4. This valve chamber is provided with a threaded boss 5, which screws into a threaded seat in a block 6, and the block 6 in turn is provided with a threaded boss 7, by which it may be securely locked to the bottom of the casing or box containing the valve mechanism. Thus the valve chamber, which may be easily inserted or removed, acts as a support for the crane, which is free to rotate thereon, and the shell 1 acts as a guide and brace for the same.

When it is desired to deliver water to a locomotive tender, the crane is swung so that its horizontal branch extends over the track. Of course, when not in use, the horizontal branch should be held to one side of the track.

In order to prevent the accidental swinging of the horizontal arm into operative position above the track, a locking device is provided. This comprises a bolt 8, carried by a sliding rod 9, and adapted to simultaneously engage a notch 10 in a flange on the vertical branch of the crane, and a similar notch 11 on a flange of the shell 1, being partly seated in each notch, and thus securely locking the revolvable crane to the stationary shell. The notches 10 and 11 are so placed as to lie in position to receive the bolt 8 only when the horizontal arm of the crane has been swung to inoperative position.

In order to enable the fireman to unlock the crane and swing it to operative position without dismounting from the tender, a rock shaft 12 is journaled along the top of the horizontal arm of the crane, and provided with wings 13, which may be readily engaged by an iron poker, or any other convenient tool. The free end of this shaft is provided with a crank 14. A link 15 is pivoted to the upper end of the rod 9, and is provided with a slotted block 16, the crank 14 being slidably seated in the slot thereof.

Thus, as the shaft 12 is rocked, the crank 14 will engage the upper surface of the slot 17 and raise the link 15 and rod 9, withdrawing the bolt 8 from the notches 10 and 11, and 5 unlocking the crane so that it may be swung. However, should it be desired to unlock the crane from the ground, a lever 18 is provided. This lever is pivoted between ears 19 on a collar 20, which is revolubly mounted 10 on the crane, and has a toe 21 which engages under a lug 22 of the bolt 8, thus raising the bolt and freeing the crane. The collar 20 is secured to the crane by means of set screws 23, which travel freely in a groove between 15 flanges 24 and 25.

When it is desired to use the lever 18, it is locked in inoperative position by means of the link 26, which passes through slots in the ears 19, the slots being so placed that they 20 will be between the toe 21 and the lug 22 when the lever 18 is raised to inoperative position. Consequently, the link 26 will lie across the path of the toe and hold the lever raised, all as clearly shown in Fig. 3. A 25 screw or other device 27 is passed through one ear 19, in such position as to lie between the opposite bars of the link and prevent it from falling entirely out of the ear, and a small padlock 28 is adapted to engage the 30 projecting free end of the link when the link has been passed through both ears to hold the lever 18 raised.

When the crane has been swung to position for delivering water, the fireman grasps 35 the elbow lever 29, which is pivoted to a bracket 30 on the crane, and swings it to full line position, as shown in Fig. 2. By swinging the lever, the rod 31, pivoted to the elbow thereof, is pushed back, rocking the 40 bell cranks 32, and forcing down the rods 33. To the rods 33 is secured a collar 34, which is loose to both slide longitudinally of and rotate freely about the crane, and seated in the groove in this collar in such 45 manner as to allow the first collar to rotate freely within it is a second collar 35, to which are connected short rods 36. The lower ends of these rods 36 are coupled to toggles 37, which operate a swinging valve. 50 In order to prevent rotation of the collar 35, and consequent twisting of the rods 36, a guide rod 41 is passed loosely through an opening in the collar 35 and secured at its opposite ends to the base of the shell 1, and 55 to the exit pipe respectively. Thus, it will be seen that although the collar 35 is free

to travel longitudinally with the collar 34, it cannot turn with said collar. To prevent injury to the valve and to the valve seat of the main, when closing off the supply, a stop 60 or limit device has been provided. This comprises a box 42 on each side of the exit pipe, adapted to loosely receive and guide the free arms 43 of the toggles 37. In the ends of these boxes are secured adjusting 65 screws 44. By adjusting these screws in or out of the boxes, they may be made to engage the ends of the arms 43 at different positions, and to thus limit the upward movement or straining of the toggles. By 70 limiting the upward movement of the toggles, the closing or seating of the valve 38 on the main for shutting off the water may be regulated as desired.

It is clear that many changes in the construction of the several parts of the invention, many substitutions for these parts, many rearrangements of them and many other combinations may be had, without in any way departing from the field and scope 75 of the invention, and it is meant to include all such within this application, wherein only one preferred form of the improvement has been illustrated and described.

Having thus fully described our invention, what we claim as new, and desire to secure by Letters Patent, is:—

1. In a water crane, a tubular shell adapted to freely receive the upright branch of a crane, means for locking said upright branch 90 and shell together, a collar slidably mounted on said upright branch, means for sliding said collar, rods connected to said collar, toggles connected to said rods, and a feed valve connected to said toggles. 95

2. In a water crane, a tubular shell adapted to freely receive the upright branch of a crane, means for locking said upright branch and shell together, a collar slidably mounted on said upright branch, means for sliding 100 said collar, rods connected to said collar, toggles connected to said rods, a feed valve connected to said toggles, and means for limiting the movement of the toggles and valve in one direction. 105

In witness whereof we have hereunto set our hands in the presence of two witnesses.
